UNITED STATES PATENT OFFICE

HENRY J. GEBHARDT, OF CHICAGO, ILLINOIS, ASSIGNOR TO THE GEBHARDT CO., OF CHICAGO, ILLINOIS, A CORPORATION OF ILLINOIS

HEAT TRANSFER APPARATUS

Application filed February 3, 1930. Serial No. 425,434.

This invention relates to heat exchange apparatus, and more particularly to apparatus of this kind for transferring heat from heated water to cold or partially heated water.

5 Generally stated, the object of the invention is to provide a novel and improved construction whereby pipes arranged in groups, with the groups connected in series in a horizontal plane, form a back and forth path for the water to be heated, while an outer structure encloses said pipes and forms a back and forth path for the heating water in which the pipes are submerged.

10 Another object is to provide an apparatus of this kind that can be used for conserving the heat in used wash water, in laundries, for heating the incoming fresh water, wash water of this kind being ordinarily thrown away without saving or using the heat thereof.

15 Another object is to provide an improved construction and arrangement whereby the flow of the heating water outside the pipes is up and down between the pipes, whereby the path of travel of the heating water is in effect longer and the heat thereof practically all transferred to the water in the pipes, before the heating water leaves the apparatus.

20 Another object is to provide novel and improved means whereby the water to be heated is evenly or more evenly circulated in the pipes, whereby the flow may be regulated more or less, thereby to prevent the water from becoming dormant in any of the pipes, and permitting the use of a large number of pipes, of comparatively small diameter, thus greatly increasing the heat exchange surface.

25 It is also an object to provide novel and improved construction whereby an apparatus of this character may be conveniently inspected and cleaned and repaired.

30 It is also an object to provide certain details and features of construction and combinations tending to increase the general efficiency and desirability of a heat exchange apparatus of this particular character.

To the foregoing and other useful ends, the invention consists of matter hereinafter set forth and claimed and shown in the accompanying drawings, in which—

35 Fig. 1 is a plan section of the invention.

Fig. 2 is a longitudinal vertical section on line 2—2 of Fig. 1.

Fig. 3 is a vertical cross-section on line 3—3 of Fig. 1.

Fig. 4 is a detailed cross-section illustrating the high baffle. 55

Fig. 5 is a section on line 5—5 of Fig. 4.

Figs. 6 and 7 are detailed perspective of parts of the baffle.

Fig. 8 is a detailed section illustrating the low baffle. 60

Figs. 9 and 10 are perspective views of parts of the low baffle.

Fig. 11 is a section on line 11—11 of Fig. 12. 65

Fig. 12 is a section on line 12—12 of Fig. 11.

Fig. 13 is a section on line 13—13 of Fig. 12.

Fig. 14 is a detailed section on line 14—14 of Fig. 11. 70

As thus illustrated, the invention comprises a tank or pit 1 of cement or masonry or other suitable material. The tank has parallel longitudinal partitions 3, 4 and 5 that divide the tank or container into parallel compartments 6, 7, 8 and 9, which compartments are connected in series to form a back and forth path of travel for liquid. The compartment 6 has an inlet 10 for used wash water, or other heated liquid, and the compartment 9 has an outlet 11 for said liquid. 75

Groups of pipes 12, 13, 14 and 15 are located in the compartments 6, 7, 8 and 9, respectively, as shown in Fig. 1 of the drawings. Suitable coupling elbows or flanged unions 16 are provided for connecting said pipe groups in series. The group 15 has an inlet connection 17, and the group 12 has an outlet connection 18, as shown, for the fresh water to be heated. 80

Baffles are provided transversely in the different compartments 6, 7, 8 and 9, to cause the wash water to flow up and down between the pipes, as follows: 85

The alternate baffles 19 are relatively high, as shown in Fig. 4, to permit the water to pass under. A plate 20 having its edges formed with grooves 21 is mounted on the pipes. The baffle 19 is shaped (inverted U-shape) with inner vertical edges 22 to slide down in the grooves 21, and with outer vertical edges 23 to slide down in the vertical grooves 24 in 90

the walls of the tank. This leaves space 25 below each baffle 19 for the passage of the water or other fluid.

Each intermediate baffle is constructed as shown in Figs. 8, 9 and 10 of the drawings. Each baffle comprises an upper plate 26, of inverted U-shape, and a lower plate 27 which seats on the bottom of the tank and forms the base of each baffle. A plate 28, similar to the plate 20, is mounted on the pipes, and the upper plate 26 slides down in the grooves 29 of the tank and the grooves in the edges of the plate 28, as shown. The upper edge 30 of the plate 27 enters the groove in the plate 28, and the lower ends of the plate 26 rest on the shoulders 31 of the plate 27 as shown. Also, lower inner edge portions of the plate 26 are held in guides 32 formed on the plate 27, whereby the plates 26 and 27 interlock to form with the plate 28 a baffle that compels the water to pass over after moving upward between the pipes. A small opening 33 is provided in the base of the plate 27, to permit the tank or container to be drained or emptied. A double flange 34 provides a base for the plate 27, which rests on the floor of the tank or container.

To prevent stagnation of the water in some pipes, as in the outer pipes of each group, the inlet end of each group has a distributor plate 35 as shown in Figs. 11, 12, 13 and 14 of the drawings. The plate 35 has holes 36 therein to register, more or less, with the inlet ends of the pipes held in the header 37 of each coupling. It will be seen that the ends of the pipes are swaged or spun over upon the inner side of the plate 37, as indicated at 38, forming annular heads on the surface of the header plate. The plate 35 has lugs 39 that bear against the header 37, to prevent wearing away of the pipe ends, by the up and down adjustment of the plate 35, for such wearing away would loosen the pipes. As shown, the plate 35 slides up and down in the guides 40 of the coupling casting, and upper and lower set screws 41 and 42 are provided with tapering engagement with upper end lower seats 43 and 44 on the plate 35, whereby the latter can be adjusted to change the relation of the holes 36 to the inlet ends of the pipes. In effect, therefore, the distributor plate 35 is a valve for reducing or increasing the size of the pipe inlets, in accordance with the water pressure, thereby to keep a uniform flow of water in all the pipes. When screws 41 and 42 are tightened, their tapered ends force the plate 35 toward the header 37, and the construction is preferably such that the lugs 39 firmly engage the header 37, while the plate 35 just barely touches or comes close to the pipe ends, thus in effect forming a practically tight valve seat on each pipe end.

In Figs. 2 and 3 it will be seen that the tank or pit, which for convenience may be sunk in the ground, has a removable covering 45,

which could be a floor, well above the water level in the tank. In this way, the apparatus is easily accessible, for cleaning or repairs, and the whole thing is of minimum depth. Arches 46, if desired, or any suitable means can be provided to help sustain the weight of the pipes. The low baffles, of course, sustain the weight of the pipes on the bottom floor of the pit tank.

Of course, the greater number of pipes in each group (while maintaining the cross sectional area of the group) the greater the heat exchange surface, and the higher the efficiency. However, with the tubes smaller and greater in number, the more possibility that some of them may go dead, or become dormant, as under a variation in water pressure. In such case, for example, the water in the outer pipes might be stagnant, while the entire effective flow would be confined to a few pipes at the center of the group. The distributor plates 35, however, can be adjusted to prevent this trouble, in the manner stated.

In effect, the baffles serve to lengthen the path of travel of the laundry wash water, or other liquid, in the tank or pit, thus more effectively extracting practically all the heat from the used wash water.

With the arrangement shown and described, there is a counterflow of the cold liquid to the heated liquid, as well as a cross-flow over the surfaces of the pipes. In addition, the baffle arrangement as a whole is such that the baffles can be removed easily for cleaning purposes, and this includes the plates which surround the pipes and which engage the U-shaped baffles.

It will be understood that by "tank" is meant any structure or thing that will suitably hold the wash water or other liquid from which it is desired to extract the heat.

It will be seen that the parallel pipes, those arranged in groups, are all submerged in the same horizontal plane, and that the couplings 16 and the inlet and outlet connections 17 and 18 are all submerged in the same horizontal plane, whereby the transfer of heat is continuous throughout the entire length of the back and forth path of travel of the water flow through said pipes and couplings. The compartments for the groups of pipes are all open at the tops, and the pipes and couplings and baffles are all accessible from the top of the tank, so that any coupling can be removed without disturbing any other coupling, and practically without disturbing the pipes, should such become necessary for the purpose of making repairs, or for cleaning the apparatus.

What I claim as my invention is:—

1. In heat exchange apparatus, pipes arranged in groups, horizontal couplings at opposite ends of each group for connecting the groups side by side in series to form a

back and forth path of travel for one fluid, in a horizontal plane, and means forming an enclosing tank having a separate compartment for each group of pipes, with the compartments arranged parallel in the same horizontal plane, and with the compartments connected in series to form a back and forth path of travel for another fluid in which said pipes and couplings are submerged, said groups and couplings all being accessible from the top of the tank.

2. A structure as specified in claim 1, said tank having an inlet and an outlet, said pipes having an inlet adjacent said outlet, and said pipes having an outlet adjacent said first mentioned inlet, preventing any flow in the pipes in the same direction as the flow in the tank.

3. A structure as specified in claim 1, said tank forming a discharge conduit for used wash water in a laundry, and said pipes forming an intake for fresh water, whereby any heat in the outgoing wash water serves to heat the incoming fresh water.

25 4. A structure as specified in claim 1, and a distributor adjustable at the intake end of each group of pipes, adapted to prevent stagnation of the water in the outer pipes of the group.

30 5. A structure as specified in claim 1, and a distributor adjustable at the intake end of each group of pipes, adapted to prevent stagnation of the water in the pipes of the group, each distributor comprising a plate having holes therein, each hole forming an inlet for a tube, and means to adjust said plate in the plane thereof, parallel with the plane of the adjacent pipe ends.

40 6. A structure as specified in claim 1, said compartments having baffle-plates in position to cause the fluid in said tank to travel up and down between said pipes, which baffles are all accessible from above.

45 7. A structure as specified in claim 1, said compartments having baffle-plates in position to cause the fluid in said tank to travel up and down between said pipes, which baffles are all accessible from above, said plates being some high and some low, with the low plates alternating with the high plates, there being a passage opening below each high plate, whereby the fluid passes over the low plates and under the high plates.

50 8. A structure as specified in claim 1, said compartments having baffle-plates in position to cause the fluid in said tank to travel up and down between said pipes, said plates being some high and some low, with the low plates alternating with the high plates, there being a passage opening below each high plate, whereby the fluid passes over the low plates and under the high plates, each low baffle comprising upper and lower sections having interengagement.

60 9. A structure as specified in claim 1, said

compartments having baffle plates in position to cause the fluid in said tank to travel up and down between said pipes, each baffle comprising a straddling plate of inverted U-shape and a plate engaging all the tubes and having vertical guides for inner edges of said straddling plate.

10. A structure as specified in claim 1, there being a complete counterflow of one liquid to the other with all of said couplings submerged in a plane below the tops of said groups.

11. In heat exchange apparatus, horizontally disposed parallel pipes forming heating elements, a tank for said heating elements, wherein all the pipes are submerged, said tank having an inlet and an outlet, said pipes having an inlet adjacent said outlet, and said pipes having an outlet adjacent said first mentioned inlet, preventing any flow in the pipes in the same direction as the flow in the tank, said inlet and outlet of the pipes being submerged in the same horizontal plane.

12. In heat exchange apparatus, horizontally disposed parallel pipes forming heating elements, a tank for said heating elements, wherein all the pipes are submerged, said tank forming a discharge conduit for used wash water in a laundry, and said pipes forming an intake for fresh water, whereby any heat in the outgoing wash water serves to heat the incoming fresh water, said pipes having an inlet and an outlet submerged in the same plane.

13. In heat exchange apparatus, a group of pipes forming heating elements, a tank having a compartment for said heating elements, and a distributor adjustable at the intake end of said group of pipes, adapted to prevent stagnation of the water in the outer pipes of the group.

14. In heat exchange apparatus, a group of pipes forming heating elements, a tank having a compartment for said heating elements, and a distributor adjustable at the intake end of said group of pipes, adapted to prevent stagnation of the water in the pipes of the group, said distributor comprising a plate having holes therein, each hole forming an inlet for a pipe, and means to adjust said plate in the plane thereof, parallel with the plane of the adjacent pipe ends.

15. In heat exchange apparatus, a group of pipes forming heating elements, a tank having a compartment for said heating elements, with an imperforate bottom for said compartment, and said compartment having baffle-plates in position to cause the fluid in said tank to travel up and down between said pipes, and distributing means at one end of said groups, tending to equalize the flow in the different pipes.

16. In heat exchange apparatus, a group of pipes forming heating elements, a tank

- having a compartment for said heating elements, with an imperforate bottom for said compartment, and said compartment having baffle-plates in position to cause the fluid in said tank to travel up and down between said pipes, said plates being some high and some low, with the low plates alternating with the high plates, there being a passage opening below each high plate, whereby the fluid 5 passes over the low plates and under the high plates, and distributing means at one end of said group, tending to equalize the flow in the different pipes.
17. In heat exchange apparatus, a group of 15 pipes forming heating elements, a tank having a compartment for said heating element, said compartment having baffle-plates in positions to cause the fluid in said tank to travel up and down between said pipes, said plates 20 being some high and some low, with the low plates alternating with the high plates, there being a passage opening below each high plate, whereby the fluid passes over the low plates and under the high plates, each low 25 baffle comprising upper and lower sections having interengagement.
18. In heat exchange apparatus, a group of pipes forming heating elements, a tank having a compartment for said heating elements, said compartment having baffle-plates 30 in position to cause the fluid in said tank to travel up and down between said pipes, each baffle comprising a straddling plate of inverted U-shape and a plate engaging all the 35 tubes and having vertical guides for inner edges of said straddling plate.
19. In heat exchange apparatus, a group of pipes forming heating elements, a tank having a compartment for said heating elements, there being a complete counterflow of 40 one liquid to the other, and distributing means at one end of said group, tending to equalize the flow in the different pipes.
20. In heat exchange apparatus, pipes arranged in groups, couplings at opposite ends 45 of each group for connecting the groups side by side in series to form a back and forth path of travel for one fluid, in a horizontal plane, and means forming an enclosing tank having 50 a separate compartment for each group of pipes, with the compartments connected in series to form a back and forth path of travel for another fluid in which said pipes are submerged, and a distributor adjustable at the intake end of each group of pipes, adapted to prevent stagnation of the 55 water in the outer pipes of the group.
21. In heat exchange apparatus, pipes arranged in groups, couplings at opposite ends 60 of each group for connecting the groups side by side in series to form a back and forth path of travel for one fluid, in a horizontal plane, and means forming an enclosing tank having 65 a separate compartment for each group of pipes, with the compartments connected in series to form a back and forth path of travel for another fluid in which said pipes are submerged, and a distributor adjustable at the intake end of each group of pipes, adapted to prevent stagnation of the water in the outer pipes of the group.
22. In heat exchange apparatus, pipes arranged in groups, couplings at opposite ends of each group for connecting the groups side by side in series to form a back and forth path of travel for one fluid, in a horizontal plane, and means forming an enclosing tank having a separate compartment for each group of pipes, with the compartments connected in series to form a back and forth path of travel for another fluid in which said pipes are submerged, said compartments having baffle-plates in position to cause the fluid in said tank to travel up and down between said pipes, said plates being some high and some low, with the low plates alternating with the high plates, there being a passage opening below each high plate, whereby the fluid passes over the low plates and under the high plates, each low baffle comprising upper and lower sections having interengagement.
23. In heat exchange apparatus, pipes arranged in groups, couplings at opposite ends of each group for connecting the groups side by side in series to form a back and forth path of travel for one fluid, in a horizontal plane, and means forming an enclosing tank having a separate compartment for each group of pipes, with the compartments connected in series to form a back and forth path of travel for another fluid in which said pipes are submerged, said compartments having baffle-plates in position to cause the fluid in said tank to travel up and down between said pipes, each baffle comprising a straddling plate of inverted U-shape and a plate engaging all the tubes and having vertical guides for inner edges of said straddling plate.
24. In heat exchange apparatus, a group of water pipes forming heating elements, means forming a chamber for said heating elements, a distributor adjustable at one end of said group of pipes, adapted to prevent stagnation of the water in the outer pipes of the group, tending to more or less equalize the flow of water in the different pipes, and means for introducing a heating fluid in said chamber.
25. A structure as specified in claim 24, said distributor comprising a plate having holes therein, each hole forming an opening for the end of a pipe, and means to adjust said plate in the plane thereof, parallel with the plane of the adjacent pipe ends, thereby in effect to change the size of each opening.
26. A structure as specified in claim 24,

comprising headers for the opposite ends of said group, said distributor being enclosed in one of said headers.

27. A structure as specified in claim 24, 5 said distributor being adjustable simultaneously and to the same extent for each of said pipes.

28. In a water heater, the combination of 10 a group of water pipes, a distributor adjustable at one end of said group of pipes, adapted to prevent stagnation of the water in the outer pipes of the group, tending to equalize the flow of the water in the pipes, an outlet connection at one end of said group, and an 15 inlet connection at the other end of said group.

29. A structure as specified in claim 28, 20 said distributor comprising a plate having holes therein, each hole forming an opening for the end of a pipe, and means whereby 25 said plate is adjustable in the plane thereof, serving thereby in effect to change the size of each opening.

30. A structure as specified in claim 28, 30 said distributor comprising means for in effect restricting or throttling the end of each tube.

Specification signed this 29th day of January, 1930.
